UNITED STATES PATENT OFFICE.

DELL WARD, OF GRAND RAPIDS, MICHIGAN, ASSIGNOR OF ONE-FIFTH TO JOHN KELSEY AND ONE-FIFTH TO HENRY J. HERBERT, BOTH OF DETROIT, MICHIGAN, ONE-FIFTH TO JOSEPH R. TAYLOR, OF GRAND RAPIDS, MICHIGAN, AND ONE-FIFTH TO WALLACE W. JOHNSON, OF CHICAGO, ILLINOIS.

VEHICLE-WHEEL.

No. 857,546.

Specification of Letters Patent.

Patented June 18, 1907.

Application filed April 2, 1906. Serial No. 309,403.

To all whom it may concern:

Be it known that I, DELL WARD, a citizen of the United States, residing at Grand Rapids, in the county of Kent and State of Michigan, have invented a new and useful Vehicle-Wheel, of which the following is a specification.

This invention relates to vehicle wheels, and has for its object to provide for cushioning the same in a new and novel manner without employing pneumatic or other forms of cushioned tires.

It is also proposed to embody the invention in the nature of an attachment which may be readily applied to an ordinary wheel without making any material alteration therein, and which when applied, effectually cushions the wheel at the hub so as to take up sudden shocks or jars.

With these and other objects in view, the present invention consists in the combination and arrangement of parts as will be hereininafter more fully described, shown in the accompanying drawings and particularly pointed out in the appended claims, it being understood that changes in the form, proportion, size and minor details may be made, within the scope of the claims without departing from the spirit or sacrificing any of the advantages of the invention.

In the drawing: Figure 1 is a side elevation of a wheel equipped with the cushioning means of the present invention. Fig. 2 is a diametric sectional view thereof. Fig. 3 is a fragmentary perspective view of the cushioning attachment.

Like characters of reference designate corresponding parts in all of the figures of the drawings.

The present attachment includes a broad rim 1, from the inner face of which project radial hangers 2 which are slotted longitudinally and are preferably in the nature of U-shaped clips or loops. A helical spring 3 has one terminal hooked to the adjacent hanger and its other end hooked into a screw-eye 4 which completes the attachment.

The present attachment may be applied to any ordinary wheel, such as shown in Figs. 1 and 2, and including a hub 5 formed by a metallic disk having a concentric opening 6. Spokes 7 radiate from the hub and are set

into radial sockets therein, the outer ends of the spokes carrying a felly 8.

In assembling the attachment and the wheel, the hangers 2 are placed astraddle of the felly 8 and then brazed or otherwise rigidly connected to the rim 1 of the attachment. The screw-eyes 4 are then fitted into the threaded radial sockets 9 in the outer peripheral edge of the hub, after which the springs are hooked into the hangers and the screw-eyes, whereby the wheel proper will be concentrically hung within the rim 1, and the weight of the vehicle is hung from the upper set of springs in such a manner as to take up all shocks or jars to which the rim of the wheel may be subjected.

By preference, a tubular open ended hub box 10 is fitted in the hub opening 6 and projects at opposite sides of the hub so as to obtain an extended bearing on the axle, there being an annular flange or face plate 11 carried by an intermediate portion of the box and of a diameter to entirely cover the adjacent side of the hub. Another face plate 12 having a central opening 13 for the reception of the hub box is fitted against the other side of the hub, and the two plates are connected by means of bolts or other fastenings 14 which pierce the plates and the hub. These plates serve not only to hold the hub box in place, but also prevent edgewise displacement of the spokes from the hub and form a finish for the latter.

Having thus described the invention, what is claimed is:

1. A wheel comprising a hub, spokes, a felly, a concentric rim spaced from the felly, spaced loops carried by the rim and embracing the felly, and springs extending between the closed ends of the loops and the hub.

2. A wheel comprising a hub, a felly, a rim spaced from the felly, rigid spokes secured to the peripheral edge of the hub between the side faces of the latter and connected with the felly, radially disposed loops secured to the rim between the rigid spokes and embracing the felly, and springs extending between the closed ends of the loops and the peripheral edge of the hub and disposed in alignment with the rigid spokes.

3. A wheel comprising a hub, spokes, radially disposed eyes secured to the periph-

eral edge of the hub between the side faces and alternating with the spokes, a felly, a rim spaced from the felly, slotted hangers carried by the rim and embracing the felly, and helical springs hooked into the eyes and connected with the hangers.

4. A cushioning attachment for wheels comprising a rim, spaced radially disposed loops having their opposite ends extended through the rim and secured thereto, eyes secured to the peripheral edge of the hub be-

tween its side faces, and springs connecting the eyes and the closed ends of the adjacent loops.

In testimony that I claim the foregoing as my own, I have hereto affixed my signature in the presence of two witnesses.

DELL WARD.
